(57) **CLAIM**

The ornamental design for a connecting module, as shown and described.

DESCRIPTION

FIG. 1 is a perspective view of the claimed design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

As shown in FIG. 7, the top portion of the connecting module is shown in broken lines to illustrate the environment only and forms no parts of the claimed design.
